UNITED STATES PATENT OFFICE

143,921

DESIGN FOR A PLIERS WRENCH

William A. Laird, South Gate, Calif.

Application May 1, 1945, Serial No. 119,330

Term of patent 3½ years

(Cl. D54—16)

To all whom it may concern:

Be it known that I, William A. Laird, a citizen of the United States, resident of South Gate, Los Angeles County, State of California, have invented a new, original, and ornamental Design for a Pliers Wrench, of which the following is a specification, reference being had to the accompanying drawing, forming a part thereof.

Fig. 1 is a side elevational view of a pliers wrench showing my new design; and Fig. 2 is a bottom plan.

What is claimed is:

The ornamental design for a pliers wrench, substantially as shown.

WILLIAM A. LAIRD.
